UNITED STATES PATENT OFFICE.

EDWARD T. CLEATHERO, OF ALTRINCHAM, ENGLAND.

RECIPROCATING BED-MOTION OF PRINTING AND ANALOGOUS MACHINES.

No. 862,309.

Specification of Letters Patent.

Patented Aug. 6, 1907.

Application filed July 7, 1905. Serial No. 268,889.

To all whom it may concern:

Be it known that I, EDWARD THOMAS CLEATHERO, a subject of the King of Great Britain and Ireland, and a resident of the Hollies, Barrington Road, Altrincham, 5 in the county of Chester, England, have invented certain new and useful Improvements in Reciprocating Bed-Motions of Printing and Analogous Machines, of which the following is a specification.

This invention relates to mechanism for converting 10 rotary into reciprocating motion, and more especially for slowing down and reversing the reciprocating bed movement in printing presses, and it has for its object to provide mechanism of simple construction, by which a constant speed is given to the bed during impression, 15 and by which unequal strains upon the bed are avoided in the transmission, and in which the slowing down and reversal is effected by means which are durable and incapable of being deleteriously affected by the wear to which the parts are subjected in use.

20 The invention is more particularly applicable to gear such as described in the specification of the prior British Letters patent granted to me No. 14268 of 1897, but the invention is of general application.

According to the invention, I provide a slide to 25 which I communicate a reciprocating movement from some part of the press mechanism, the motion being communicated in a movement of rotation at the same speed as that of the bed, or of that part of the mechanism with which the slide engages at or about the middle 30 of its stroke, whereby the movement of the bed may be slowed down, reversed, and an accelerating return movement given to it until it reaches the speed of the main driving mechanism of the bed, so that thus the incidental strains in reversing are taken up by the 35 slide, and are not communicated to the driving mechanism proper by which the reciprocating movements are communicated to the bed. According to the invention moreover I provide the slide to engage with the gear wheel which meshes with the bed rack, to which 40 gear wheel a rotary reciprocating movement is communicated by suitable driving gear, and for the purpose I advantageously provide a wrist-pin upon it having the same velocity as that of the slide at or about the middle of its stroke, the slide being provided with a 45 recess or recesses within which the wrist-pin engages towards the end of each stroke of the bed.

According to the invention other constructional features are involved which are hereinafter more particularly described.

50 The invention is illustrated by way of example in the accompanying drawings in which

Figure 1 represents a longitudinal vertical section of a printing press to which the invention is applied

the figure being a longitudinal section on the lines *l-l* of Fig. 2 which is a plan corresponding to Fig. 1 in 55 which the cylinder and the bed are omitted.

Referring to the drawings, *a* and *b* represent the usual side frames of a printing machine, *c* the type bed, *d* the cylinder, *e* inking rollers, *f* and *g* cross stays or girders for securing the two side frames together, *h* and *i* the 60 fast and loose driving pulleys, *j* its shaft, *k* spur pinion fast on the shaft *j*.

l and *m* are a pair of spur wheels fast respectively on shafts *n* and *o* turning in suitable bearings in the side frame *a* and bearing bracket *p*. These spur wheels 65 are of the same diameter and gear with each other, their motion being derived from the pinion *k* which engages one of them:

q and *r*, are a pair of mutilated spur wheels, having teeth on one third of their peripheries, the other two 70 thirds being mutilated or cut away, these wheels are also fast upon the shafts *n* and *o* respectively with their toothed surfaces on opposite sides of their respective shafts.

s is the shaft by which the bed is driven, and is 75 mounted to turn in suitable bearings of the side frame *a* and bracket bearing *p* equidistant of the two shafts *n* and *o*.

t is a spur wheel fast upon it and receives its motion from the mutilated spur wheels *q* and *r* alternately, and 80 the respective sizes and positions of their shafts *n*, *o*, *s*, are regulated accordingly.

u is a spur wheel likewise fast on the shaft *s* and in gear with the bed rack, *v* secured to the bed *c*.

The continuous rotary motion of the mutilated spur 85 wheels *q-r* in opposite directions will turn the pinion *t* through arcs, each one of a length proportionate to the length of the toothed surface engaging with it. The direction of rotation on the part of that pinion *t* being alternate to correspond with the direction of the respective wheel engaging with it for the time being. The bed *c* partakes that alternate motion by means of the spur wheel *u* and the rack *v* already described.

The present invention it will be understood does not relate to the construction so far described.

95 On the spur wheel *u* the crank pin *w* and roller *x* as shown on Fig. 1 has entered the slotted recess *y* of the yoked bracket *z* as the mutilated wheel *r* leaves the pinion *t*, the spur wheel *u* by means of the pin *w* engaged by the yoked bracket *z* commences to first slow down the motion of the bed gradually to a full stop and gradually starts it in the reverse direction up to the peripheral speed of the mutilated spur wheel *q* and the pinion *t* when they engage with each other and continue the bed motion in the opposite direction at a uniform speed until it nears the end of its travel, when the 100 105

crank pin *w* engages in the slotted recess *y'* and slows down and reverses the bed again. The yoked bracket *z* is carried in slide guides A—B and is driven by the crank pin *C* connected to the disk *E* mounted on the 5 shaft *F* with the fast spur pinion wheel *G* in gear with the spur wheel *l* the proportionate ratio of the pinion wheel *G* being three revolutions to one of the spur wheel *l*. The yoked bracket travels three times in each direction to the travel of the bed once in each direction.

10 It will be understood that as the last teeth of the mutilated wheel are leaving the pinion *t*, as indicated by the direction of the arrows on Fig. 1, the pin *w* engages the yoked sliding bracket *z* in the recessed slot *y*, and the pin *C* attached to the disk *E* arrives at its top 15 central position, the maximum speed of travel of the yoked sliding bracket being then attained in synchronism with the peripheral speed of the pin *w*, when the disk, moving to the next quarter of its revolution, slows the bed down to stop, and reverses gradually to full 20 speed on the pin *C* reaching the bottom central position of the slotted guide *H*. The wheel *q* has by then engaged the pinion *t* and the pin *w* moves out of engagement with the yoked sliding bracket.

The wheels *q*—*r* fixed on their respective shafts at opposite positions to each other and having teeth on one third only of their peripheral area there is nearly one sixth of their periphery when neither wheel is in gear with pinion *t* during each half revolution of the wheels *q*—*r*; during this portion of disengagement the yoked 30 sliding bracket *z* has engaged the pin *w* on wheel *u* and accomplished the act of reversing the motions of travel when the opposite wheel engages in gear with the pinion *t* and drives the bed.

Having described my improvements in one form in 35 accordance with the drawings attached I may modify the gearing and positions of the yoked sliding bracket, instead of a sliding yoked bracket I may use a rocking bracket or sector yoked to a crank pin and two racks

under bed and rack wheels instead of one without departing from the novelty of this invention in any way. 40

What I claim as my invention and desire to secure by Letters Patent is,

1. In mechanism for converting rotary into reciprocating motion, a slide to which a reciprocating motion is given, a bed, a gear wheel gearing with the bed, a pair of mutilated gear wheels for giving said gear wheel a rotary reciprocation and means to engage said slide with said gear wheel during a portion of each revolution substantially as described. 45

2. In mechanism for converting rotary into reciprocating motion, a slide to which a reciprocating motion is given, a bed, a gear wheel gearing with the bed, a pair of mutilated gear wheels for giving to said gear wheel a rotary reciprocation and a wrist pin and slot connection between said slide and said gear wheel during a portion of each revolution substantially as described. 50

3. In mechanism for converting rotary into reciprocating motion, a bed, a gear wheel gearing with the bed, a pair of mutilated gear wheels for giving to said gear wheel a rotary reciprocation, a slide to which three reciprocations are given for each reciprocation of the bed, and means to engage said slide with said gear wheel during a portion of each revolution substantially as described. 55

4. In mechanism for converting rotary into reciprocating motion, a slide to which a reciprocating motion is given, a bed, a gear wheel gearing with the bed, a pair of mutilated gear wheels for giving to said gear wheel a rotary reciprocation, and a wrist pin and slot connection between said slide and said gear wheels substantially as described. 60

5. In mechanism for converting rotary into reciprocating motion, a bed, a gear wheel gearing with the bed, a pair of mutilated gear wheels for giving to said gear wheel a rotary reciprocation, a slide to which three reciprocations are given for each reciprocation of the bed, and a 75 wrist pin and slot connection between said slide and said gear wheel substantially as described.

In testimony whereof I have signed my name to this specification.

E. T. CLEATHERO.
